UNITED STATES PATENT OFFICE.

WILLIAM VOGEL, OF CHICAGO, ILLINOIS, ASSIGNOR, BY DIRECT AND MESNE ASSIGNMENTS, TO THE VOGEL PETROLEUM HEATING COMPANY, OF SAME PLACE.

HEATING DEVICE.

SPECIFICATION forming part of Letters Patent No. 390,194, dated September 26, 1888.

Application filed August 24, 1886. Serial No. 211,711. (No model.)

To all whom it may concern:

Be it known that I, WILLIAM VOGEL, of Chicago, in the county of Cook and State of Illinois, have invented certain new and useful 5 Improvements in Heating Devices; and I do hereby declare that the following is a full, clear, and exact description thereof, reference being had to the accompanying drawings, and to the letters of reference marked thereon, 10 which form a part of this specification.

A heating apparatus embodying my invention comprises as its main feature of novelty a fire-place or other equivalent space or chamber provided with an exit-flue for products of combustion, a burner for gas, vapor, or oil located at the bottom of said chamber, and a 15 thin metal plate, sheet, or shell located in the said chamber in such manner as to form a radiating-surface exposed to the air of the apartment in which the heater is located, the said plate, sheet, or shell being located over the burner in such manner that the flames therefrom shall pass immediately over and in contact with the said metal plate, sheet, or shell, 20 whereby the latter will be maintained at a red or white heat and will thereby present an agreeable appearance of a glowing or incandescent body present in a coal fire, but absent in gas or oil heating apparatus as heretofore 25 commonly made.

Another feature of my invention comprises a metal plate or shell which is heated by the passage over it of the flames from a gas, vapor, or oil burner, and which is made with prominences or projections, making the metal of the plate thicker in some parts than in others, so that when the plate or shell is heated to a sufficient extent the thinner parts will appear 35 or incandescent and the thicker parts of darker 40 color or black, according to the relative thickness of metal in the different parts of the casting, the said projections or prominences preferably being arranged to form an ornamental figure or design, which will appear in darker 45 shades upon the glowing body of the heated plate or shell. The exterior or visible surface of the plate or shell will be made smooth, and the prominences or projections forming the

figure or design will be made upon the rear or concealed side thereof, so that the figure or 50 design will be visible only when the plate or shell is heated.

One desirable form of oil-burner for use in connection with a plate or shell of the character above described is herein shown, such 55 burner being similar to one shown and claimed in a prior application, Serial No. 210,046, filed by me in the United States Patent Office August 5, 1886, certain novel features of construction in the said burner, whereby it may be more advantageously employed in connection with a 60 plate or shell of the character above described, being shown and made the subject of claims herein.

In the accompanying drawings, Figure 1 is 65 a front elevation of a fire-place heater embodying my invention, a part of the front wall thereof being broken away to show interior parts in section. Fig. 2 is a central vertical section of the same, taken upon line $x-x$ of Fig. 70 3. Fig. 3 is a sectional plan view taken upon the horizontal line $x-x$, Fig. 1. Fig. 4 is a fragmentary front elevation of a fire-place heater, illustrating a modified form thereof. Fig. 5 is a similar view, slightly differing from that 75 shown in Fig. 4. Fig. 6 is a sectional view through a fire-place, illustrating a burner generally similar to that shown in Fig. 1 in connection with a different form of shell. Figs. 7, 8, and 9 illustrate an ornamental appear- 80 ance which may be given to the front face of a sheet or shell heated to redness by means of suitably-shaped projections upon the rear surface of the said sheet or shell. Fig. 10 is a detail section illustrating the air-inlet valve of 85 the burner.

In the said drawings, A indicates a metal plate or shell, B a burner located beneath said plate or shell for heating the latter, and C a fire-place in which the parts mentioned are 90 placed.

The burner B (shown in Figs. 1, 2, and 3) is generally similar to that shown in the prior application above referred to.

In the form of the burner herein illustrated, 95 D is an outer box or casing open at its top and

closed at its bottom, with the exception of an opening, D', for the admission of air to the burner, which opening is provided with a valve, d.

5 E is a box or shell located within the casing D and supported above the bottom of the latter by lugs e, said box E being open at its top and closed at its bottom.

F is a shallow box or pan sustained by legs 10 f from the bottom of the shell E, and G is a bottomless shell or frame sustained over the pan F, with its lower margins above the bottom of said pan, preferably by lugs g upon the frame resting upon the said pan.

15 H is a vertically-perforated bed filling the lower open end of the shell or frame G.

I is a cast-metal deflecting-plate sustained within the upper part of the casing or shell G, with its lower edge near the top of the bed H, 20 said casting being provided at its top with an outwardly-extending flange, I', which rests at its outer edge upon the top of the outer box or shell, D, and closes the space at the top of the burner between the casting I and the said 25 box or shell.

J is an oil-supply pipe, which is herein shown as extending horizontally beneath the floor of the room in which the burner is situated to a point beneath said burner, and which extends 30 upwardly through the bottom of the casing D and box E and is secured in the bottom of the pan F.

The burner comprising the parts above described operates in the same manner as does 35 the burner described in the said prior application, the oil from the pipe J entering the pan F and rising through the perforated bed H, while the air admitted through the opening D rises through the space between the 40 side walls of the parts D and E, and then passes downwardly between the frame G and the deflecting-plate I to the upper surface of the bed H, where combustion takes place, the flames rising through the central space or opening 45 formed within the deflecting plate I. The lower edge of the deflecting-plate I is arranged above the top margin of the pan F, so as to allow the overflow of oil over the top of said pan before it rises sufficiently high within the frame 50 G to cut off the passage for air between the said lower edge of the deflecting-plate and the top of the perforated bed, as fully set forth in the said prior application.

In Figs. 1, 2, and 3 is shown a hollow globe 55 or spherical shell, A, which is sustained over the burner B in such manner that its lower surface forms with the flange I' of the deflecting-plate I an annular exit-passage, i, through which the flame from the burner issues at all 60 sides of the shell, the parts being so arranged that the sheet of flame issuing from the passage i passes upwardly over the outer surface of the shell A, the smoke and products of combustion passing away through the exit flue C' 65 of the fire-place, which flue is arranged above the top of the spherical shell, so that the flame will be drawn or carried by the chimney-draft

over the top surface of the shell or a greater part thereof.

The shell A in the figures referred to is 70 made vertically movable to enable the width of the passage i to be increased or decreased, and the size of the heating-flame thereby changed as desired, and for this purpose said shell is sustained by means of a rigid stem, K, 75 preferably constructed to slide vertically in a stationary tubular guide-standard, K', located in the rear part of the fire-place. Suitable means are provided for moving said stem vertically and holding it in its changed position, 80 whereby the shell may be raised and lowered as desired. The device for this purpose illustrated and preferably employed consists of a horizontal shaft, K'', provided with a gear-pinion, k, intermeshing with a rack, k', upon the 85 stem K, the said shaft being provided upon its outer end with a hand-crank, K'', whereby the shaft may be turned. Any suitable means may be employed for locking the shaft from movement, that herein shown consisting of a 90 movable pin, k'', adapted for engagement with either one of a number of holes, k', in a stationary segment, K'.

The valve d, Fig. 10, controlling the air-inlet opening D' of the burner, preferably consists of a plate attached to the shaft K'', and so arranged that when the shaft is turned in a direction to lower the shell A, and thereby close the passage i, the said valve will be closed, and when the passage i is opened by a reverse 100 movement of the shaft the valve d will be similarly opened. By this means the air-inlet opening will obviously be controlled to supply the quantity of air necessary for a large or small flame without requiring any special 105 attention by the operator to secure this end.

The fire-place shown is provided with an ornamental front piece, C'', and with a horizontal bottom plate, C', upon which the burner B is sustained, and which forms the bottom of 110 the box D. The shaft K'' is located beneath said bottom plate, and the front piece, C'', is provided with openings e to admit air below the plate to the inlet-opening D' of the burner.

A' A', Figs. 1, 2, and 3, are wings or shields 115 placed at the sides of a shell used in a fire-place to deflect the sheet of flame passing from the rear part of the passage i to and over the front or visible part of the shell. The shell, furthermore, is provided with an opening, a, 120 in its bottom over the central opening of the burner and a second opening, a', in its top. When the shell is lowered and the valve d closed to extinguish the burner-flame, the gas or vapor thereafter generated from the oil then 125 contained in the heated porous bed H passes upwardly through the said openings and burns at the top opening, a', until all of such gas or vapor is consumed. A part of the flame from the burner will commonly pass into the interior of the shell A through the lower opening, a, thereby facilitating the heating of the shell.

The shell A (shown in Figs. 1, 2, and 3) is shown in Fig. 2 as provided in its front part

with prominences or projections a^2 a^3 upon its inner surface. The main part or body of the shell will be made sufficiently thin to become heated to a red or white heat by the flame passing over it; but the said prominences or projections, being thicker, will become heated to a less degree, and will therefore afford dark figures upon the glowing surface of the shell when the latter is heated. The appearance of

10 the shell, in which the said prominences are made in the form of a central boss and an encircling ring when the shell is heated, is shown in Fig. 1. Ornamental designs of any kind may obviously be made by giving suitable 15 shape and thickness to the prominences, as illustrated, for instance, in Figs. 7, 8, and 9.

A metal plate or shell adapted to be heated to redness by the burner-flame in the manner above described may be of other than spherical shape and may be irregular instead of symmetrical in form. In Figs. 4 and 5, for instance, I have illustrated a metal shell shaped to imitate a number of pieces of wood piled together and a pile of coal. The shell in such 25 case will preferably be made with openings or perforations a^4 , Fig. 5, to allow the passage of the flame through and over all parts of the irregularly-shaped shell. In the use of a shell of this kind a natural appearance of the objects imitated may be more closely obtained by varying the thickness of the metal of the shell, so that portions thereof shall appear dark, while others are heated to redness or to 30 a state of incandescence, as above set forth.

35 In carrying out the general features of the invention, as above set forth, it is entirely obvious that the flame for heating the shell may be applied either inside or outside of the latter, or to both the inside and outside thereof. A construction is illustrated in Fig. 6, for instance, in which the central flame-exit opening, i , of the burner B is connected with the interior of a shell, A, the products of combustion passing from an opening, a^5 , at the top of said shell. 45 The shell shown in said Fig. 6 is generally flat in form with a rounded outer surface; but a shell thus heated may be otherwise made in practice as found convenient or desirable.

A burner of the character herein illustrated 50 is of especial advantage for use in connection with a plate or shell in the manner herein described, and certain features of construction in said burner, whereby it may be conveniently applied for heating said shell, are therefore 55 herein claimed as part of my invention.

It is to be understood that my invention, as it relates to a plate, sheet, or shell provided with prominences or projections forming ornamental designs thereon, may be employed 60 in connection with a gas or vapor burner, or any other kind of heating device adapted to retain such plate, sheet, or shell at a red or white heat.

I claim as my invention—

65 1. A heating apparatus comprising a fire-place or other open space or chamber provided with a smoke-exit flue, a burner for gas,

vapor, or oil, located in the lower part of said fire-place or chamber, and a hollow metal shell forming the heat-radiating surface of the apparatus and located within said fire-place or chamber above the burner in such manner that the flame from the burner will pass over the shell and heat the same to a state of redness or incandescence, substantially as described. 70 75

2. A heating apparatus comprising a hollow metal shell forming the heat-radiating surface of the apparatus, a burner for gas, vapor, or oil, located beneath said shell in such manner that the flames from the burner will pass over or in contact with the shell, and thereby heat the latter to redness or incandescence, the said shell being provided with projections or prominences, which will appear dark in color upon the shell when the latter is heated, substantially as described. 80 85

3. A heating apparatus comprising a hollow metal shell made smooth upon its exterior surface and provided with projections or prominences upon its inner face, and a gas, vapor, or oil burner located beneath the said shell in such position that the flames from the burner will pass over or in contact with the shell and will heat the latter to redness or incandescence, substantially as described. 90 95

4. A heating apparatus comprising a hollow metal shell forming the heat-radiating surface of the apparatus, a burner comprising an oil holder or receptacle, means for supplying oil to said receptacle, and a combustion-chamber over said receptacle, having a peripheral flame-outlet adjacent to the said shell, substantially as described. 100

5. The combination, with a burner provided with a chamber within which combustion takes place, of a hollow metal shell located over the chamber and forming with a part or wall of the burner a peripheral flame-opening, and means for moving said shell vertically, whereby the said opening may be opened and closed at will, substantially as described. 105 110

6. A heating apparatus comprising a shell, G, a perforate bed forming the bottom of said shell, means for supplying oil to said bed, a deflecting-plate, I, forming with the side walls 115 of said shell G, an air-passage leading to the part of the combustion-chamber adjacent to the bed, and a hollow metal shell located over the combustion-chamber and forming, with the upper margin of the said plate I, a peripheral 120 exit-opening to said chamber, substantially as described.

7. The combination of a burner provided with an air-inlet opening and a vertically-movable shell sustained over said burner and forming with the upper part or casing of the burner a peripheral exit-opening, a vertically-movable stem, K', sustaining said shell and provided with a rack, a horizontal shaft, K², provided with a pinion engaging the rack upon the stem K', a valve, d, attached to and moved by the shaft K², and means for turning said shaft and for locking it in its changed position, substantially as described. 125 130

8. The combination, with an oil, vapor, or
gas burner, B, of a hollow metal heat-radiating
shell, A, located over the said burner and pro-
vided with lateral deflecting flanges A' A', ex-
5 tending along the sides of said shell from the
lower to the upper portion of the latter, sub-
stantially as described.

In testimony that I claim the foregoing as my
invention I affix my signature in presence of
two witnesses.

WILLIAM VOGEL.
